UNITED STATES PATENT OFFICE.

WALTER E. UHRLAND, OF ST. LOUIS, MISSOURI.

GAME-BOARD.

No. 918,799.

Specification of Letters Patent.

Patented April 20, 1909.

Application filed December 22, 1908. Serial No. 468,748.

To all whom it may concern:

Be it known that I, WALTER E. UHRLAND, citizen of the United States, residing at St. Louis, State of Missouri, have invented certain new and useful Improvements in Game-Boards, of which the following is a full, clear, and exact description, reference being had to the accompanying drawings, forming a part hereof.

10 My invention has relation to improvements in game-boards; and it consists in the novel details of construction more fully set forth in the specification and pointed out in the claims.

15 In the drawings, Figure 1 is a perspective view of my invention; and Fig. 2 is a vertical longitudinal section taken through the hinged arm or bat by which the play-ball is struck.

20 The object of the present invention is to construct a game-board in which an imitation base-ball game can be played in-doors, the same conforming in details as near to the natural game as is possible with any 25 artificial or substitute means restricted to a limited space.

A further object is to provide a board on which the game may be played by two, four or any even number of persons; one in which 30 chips or disks are employed to indicate the runners or batters, and one possessing other features of construction the purpose of which will be best apparent from a detailed description of the invention which is as follows:

35 Referring to the drawings, B. represents a board or platform having a marginal circumscribing ledge or wall 1, along two sides of which are formed in the board a row of twenty depressions or pockets 2, the corner 40 pocket being counted as belonging to either row. On the wall 1 over the last or outer three pockets of each row is marked the word "Foul", the remaining designations starting with the left hand end of the series, being 45 marked over the successive pockets as follows: 3 B, O, O, 2 B, H R, O 1 S B, O, 1 B, O, 2 B, O, 1 B, O, 1 B, O, O, 2 B, 1 B, O, O 1 S B, 1 B, O, 1 B, O, 1 B, 3 B, O 1 S B, 1 B, O, 1 B, O, H R.

50 From the inner of each set of "foul" pockets and disposed parallel to the respective sides of the board (which is preferably square) are lines a a, which meet at a point at which the batter or striker is supposed to 55 be stationed as presently to be explained. Leading from each of the lines a a, at suitable

distances from the ends thereof, and drawn at right angles thereto are lines b b which intersect or meet at what constitutes the second base pocket 2 B, the meeting points of the lines b b with the lines a a, indicating the positions of the first base pocket 1 B, and the third-base pocket 3 B as shown, the fourth base being without a pocket since the bat plays over this base as presently to appear. Between the lines b b and the adjacent sides of the board, are conveniently marked off by lines x x, y y as shown, outer sections or areal divisions S, O, O, S, O, O, S, immediately adjacent to the pockets 2, 60 and an inner series of divisions O, S, S, O, located adjacent to the "diamond" formed by the lines a a b b. Along the lines x x, are marked off the right field pocket R F, and left field pocket L F, respectively, the center-field pocket C F, being at the point of intersection of the lines x x. Between the second and third base pockets on one of the lines b is the short-stop pocket S S, and at the corner of the board behind the striker is the 70 catcher's pocket C. The lines b b with the lines a a mark off a square which is divided by the diagonal "play-ball" line d into two sections marked each with the letter O. The designations S and O mean respectively 75 "safe" and "out" and will be presently referred to.

Mounted adjacent to the corner or point of intersection of the lines a a is a bearing or block 3 provided with a pin 4 about which is 80 free to oscillate the arm or bat 5, the free end thereof being provided with a lateral offset or head 6, which as it sweeps along the board, leaves a space between the arm and the surface of the board, for the free passage or rolling therethrough of the ball or marble m used in the game. The runners representing the players on opposite sides are indicated by chips or disks n colored on one side in the present illustration red the opposite side of the chip being without any special color or left uncolored. The designations O, S, 1 B, 90 2 B, 3 B, H R, O 1 S B, mean respectively "out", "safe", "1 base hit", "2 base hit", "3 base hit", "home run", "out on first 95 base—steal a base".

To play the game, an intimate knowledge of out-door base-ball is not absolutely necessary, an understanding of the main terms employed being sufficient. With the explanation of the meaning of the designations already given, the operation of the device 100 105

may be described as follows: Suppose two persons are playing the game, and the runner identified by the red chips is at the bat. The pitcher (the opposite player) rolls the ball or marble along the play-line from second base toward the base occupied by the striker or runner who with his hand swings the bat or arm 5 toward the right or across the base (this being at the intersection of the lines *a* 10 *a*). If he strikes the ball thus rolling toward him and by the impact drives the ball say into one of the pockets 2 identified by the designation 1 B, that means that he has made one base hit or a run to the first base, 15 and accordingly a red chip is placed at the first base pocket 1 B. If he fails to strike the ball and the latter rolls under the arm 5 (through the space formed by reason of the offset or head 6) that is counted as one ball, 20 and should four such failures follow successively so as to result in four balls, it would entitle the runner to make a base. Of course the failure to strike a ball is due to the failure of the "pitcher" or person rolling the ball to 25 pitch it over the base across which the head 6 of the bat sweeps, and corresponds to the failure of a pitcher in an actual out of door game to pitch the ball over the plate, when, upon four such successive failures the striker 30 is entitled to his base. Assuming a striker at the first base, a fact indicated by placing a red chip at such base, and assuming that on the next rolling of the ball the striker at the bat likewise sends the ball into a pocket 35 marked 1 B. This will entitle such second striker to first base, and the previous striker to a base, or to second base, a fact indicated by moving the chip which was at first base to second base, and placing a fresh chip at the 40 first base. Again suppose a striker should send the ball into a pocket marked 3 B; this would entitle him to three bases, and if on the next strike he made a one-base hit, the chip on the third base would be called in and a complete 45 run would be indicated for this chip, a second chip being placed at the first base pocket 1 B to indicate the making of a base hit. Again, should the batter drive the ball into a "Foul" pocket, each foul would count a 50 strike against him, for the first two fouls just as it does in the natural game. If the batter drives a ball into a pocket marked H R, it entitles him to a home run; if he sends it into a pocket marked O 1 S B, it means he is out on 55 first base, but that the man (or chip) at the first base steals the next or second base, or that a man at any given base steals the next following base. Again, suppose the striker drives a ball into a pocket on the board 60 marked R F, it means that the man in the right field has caught the ball and the striker is "out"; if the ball lands in pocket C F, it means the man at center field has caught the ball, and the striker is out, and so on through 65 the remaining pockets in the field, including

the catcher's pocket behind the bat marked C, meaning that the catcher has caught a foul and the striker is out. Again, should the ball roll beyond the "diamond" into one of the field spaces marked O, the striker is out, 70 meaning that one of the field men caught the ball; if it lands in one of the divisions marked S, he is "safe" indicating that none of the field men caught the ball. The "diamond" above referred to is the space between the 75 four bases, bounded by the intersecting lines *a a b b*.

It will be seen from the foregoing that almost every phase of the natural game may be imitated. Of course not all, but enough to 80 make the parlor game interesting. Two persons may play it as described, the player at the bat continuing until all the chips colored to represent his side are exhausted in either making their bases, or are counted out according to where they land on the board after impact. Thereupon the opponent takes the bat and the first batter does the rolling of the ball *m*, utilizing a set of different colored chips, or he may use the same chips 85 which are colored differently on their opposite faces. Of course if four persons play, then two take one side and two the opposite side as obvious. The ball should always be rolled along the play-line *d*, otherwise it is 90 apt to pass behind the head 6 under the arm 5, and count against the roller or "pitcher" 95 who, if he rolls four such balls entitles the striker or batter to a base run.

Having described my invention what I 100 claim is:

1. A base-ball game-board comprising a four sided platform having a bounding wall or ledge extending above the face of the platform, a "diamond" marked off on the platform with sides parallel to the edges of the platform, pockets formed at the first, second and third bases of the diamond, a series of pockets formed along two sides of the wall respectively parallel to the lines connecting the first and second base pockets, and second and third base pockets, the said wall bearing marks opposite the respective contiguous pockets designating the result of a given strike of the ball projected into the 105 pocket, an arm pivoted to sweep over the platform and having a terminal lateral head bearing against the platform and spacing the arm a suitable distance from the face of the platform for the free passage of the ball 110 therethrough, the board being provided outside of the diamond with pockets properly designating and defining the positions of the center field, left field, right field, and pockets defining the position of the short-stop and 115 catcher, substantially as set forth.

2. A base-ball game-board having a diamond marked thereon, a contiguous series of divisions representing "safe" and "out" 120 positions for the ball, an outer series of simi- 125

lar divisions contiguous to the first set of divisions, two outer rows of pockets disposed along corresponding contiguous sides of the board, and walls projecting above the board
5 adjacent to the pockets and bearing inscriptions designating the result of a given strike of the ball projected into the pocket, the "Foul" pockets being positioned adjacent

but exterior to, an extension of the outer bounding sides of the diamond. ¹⁰

In testimony whereof I affix my signature, in presence of two witnesses.
